UNITED STATES PATENT OFFICE.

BERNHARDT JORGENSEN, OF BEVERLY, MASSACHUSETTS, ASSIGNOR TO UNITED SHOE MACHINERY CORPORATION, OF PATERSON, NEW JERSEY, A CORPORATION OF NEW JERSEY.

MACHINE FOR WORKING UPERS OVER LASTS.

Application filed August 29, 1921. Serial No. 496,202.

This invention relates to machines for working uppers over lasts, and is herein illustrated in its application to machines for pulling over uppers and for lasting the toe ends of the shoes. It will be recognized, however, that while in some aspects the invention is particularly appropriate to machines of the type illustrated, in many of its features it is not limited to an organization 10 including both pulling-over means and toe lasting means.

Machines have been devised heretofore for pulling over uppers and lasting the toe ends of the shoes, as illustrated for example, in 15 one form, in United States Letters Patent No. 1,280,613, granted on October 1, 1918, upon an application of Orrell Ashton, machines of the general type shown in said patent being used principally in the manu- 20 facture of turn shoes. An object of the present invention, among others, is to provide an improved pulling-over and toe lasting organization, and in one aspect the invention aims to provide an organization adapted for 25 lasting McKay shoes where the toe portion of the upper is formed by the lasting operation in the shape which it is to have in the finished shoe and is permanently secured to the insole. Further objects are to provide im- 30 provements in end lasting means, and to pro- 35 vide for better operation and control than heretofore of overlaying and upper fasten- 40 ing mechanisms.

For the accomplishment of the above and 35 other objects, the invention provides a novel organization of means for working an upper tightly into lasted position about an end 40 of a shoe and for fastening it in lasted position. For the purposes of McKay shoe work, 45 the machine herein shown comprises toe embrac- 50 ing wipers and means for operating them to gather and wipe the margin of the upper inwardly about the toe, and means for driving McKay lasting tacks to their permanent 55 positions in the shoe for fastening the upper. Further features are to be recognized 60 in novel means for increasing the pressure of overlaying or wiping means on a shoe by relative movement between such means and 65 the shoe in a direction transverse to the plane of the shoe bottom, the machine illustrated 70 having means for wedging the toe embracing wipers toward the plane of the shoe bottom 75 as they are forced inwardly over the shoe,

and means for applying to them additional 55 upper compacting and holding pressure after they have been forced inwardly. In operating on McKay shoes, for example, this insures that the upper will be gathered and wiped tightly and smoothly inward over the 60 insole and held securely until the tacks are driven. In the type of machine illustrated, such control of the wipers is effected through the front and side arms, which are moved inwardly to close the wipers over 65 the shoe and receive subsequently a movement transverse to the plane of the shoe bottom to increase the wiper pressure.

A further feature of the invention con- 70 sists in novel means designed to insure effective control of upper securing fastenings to position them relatively to the plane of the shoe bottom for the fastening operation. In the machine illustrated the fastening devices or tackers are carried by the front and side 75 arms and comprise tack holders which are moved toward the plane of the shoe bottom by the above described movement of the arms for increasing the wiper pressure. Such an organization permits the upper securing fastenings or tacks to be effectively controlled in the driving operation without the necessity for using longer tacks than are desirable, 80 this being a particularly useful feature in McKay shoe work where the tacks are to be 85 fully driven.

Still another feature of the invention con- 90 sists in improved means for moving overlaying or fastening mechanism inwardly over a 95 shoe and for controlling such mechanism in its relation to the shoe. In its embodiment of this feature the machine shown has supplemental means in addition to the usual wedge blocks to assist in moving the front and side arms inwardly and in holding them 100 against retractive movement prior to the driving of the tacks, thus insuring against any displacement of the arms and their supported tacking mechanisms prior to or at the time when the tack drivers are released for their operative movements by the slipping of the wedge blocks. An additional advantage of 105 this feature in the illustrated organization is that the wipers are held securely in position over the shoe bottom at the time when they are forced toward the plane of the shoe bottom by the bodily movement of the arms.

The above and other features of the inven-

tion, including also novel means for determining adjustably the position of upper securing fastenings and the limit of overwiping movement, and various details of construction and combinations of parts, will now be described with reference to the accompanying drawings and pointed out in the claims.

In the drawings,

10 Fig. 1 is a view in side elevation of the head portion of a machine in which the invention is embodied;

15 Fig. 2 shows in side elevation a portion of the pulling-over and lasting means at the end of the toe;

20 Fig. 3 is a view approximately in front elevation, with parts in section, showing portions of the pulling-over and lasting means at the sides of the forepart;

25 Fig. 4 is a view similar to Fig. 2 illustrating the positions of the parts at the end of the toe lasting operation, with the tack drivers at the end of their driving movement;

30 Fig. 5 illustrates by reference to one side portion of the mechanism shown in Fig. 3 the conditions at the same stage in the cycle as that illustrated by Fig. 4;

35 Fig. 6 is a view approximately in plan, with parts in section, showing the mechanism for moving the front and side arms inwardly and outwardly and for releasing the tack drivers;

40 Fig. 7 is a section substantially on the line 7—7 of Fig. 2 illustrating the manner in which the front and side arms are mounted for downward and upward movements;

45 Fig. 8 is a perspective view of the toe wipers; and

50 Fig. 9 is a perspective view showing the toe end of a McKay shoe as it appears after the pulling-over and lasting operations of the machine.

The invention is illustrated in its application to the type of machine shown in said prior Ashton patent, some of the characteristics of this well-known type of machine being shown and described in greater detail in other prior patents including Patent No. 1,029,387, granted on June 11, 1912, upon an application of R. F. McFeely, to which reference may be made for a more complete understanding of the details of the structure not hereinafter particularly described. In common with other machines of this general

55 type, the machine shown includes in its organization a toe gripper 2 and side grippers 4 connected respectively to updraw levers 6 and 8 which are operated through yielding connections by cams on a cam shaft 10. The

60 shoe is presented with its sole or insole, hereinafter frequently termed for convenience the "sole", in engagement with a sole rest 12, and in the first stage of the cycle of the machine, when the grippers are operated to pull 65 the upper, the sole rest is rocked downward-

ly to depress the last within the upper and a heel rest 14 is moved forwardly into supporting engagement with the heel end of the shoe, whereupon the machine comes automatically to rest with the upper held under tension to permit any of the usual adjustments which may be required. Upon a subsequent starting of the machine clamp arms 16 are swung inwardly into supporting and holding relation to the shoe at the sides of the forepart, as illustrated in Fig. 3, and either in the same stage of the cycle or upon a subsequent actuation of the starting means, depending upon the type of control provided, the overlaying and fastening devices are operated to wipe the margin of the upper inwardly and to drive the upper fastening tacks, the parts then returning to starting position and releasing the shoe.

The overlaying and fastening devices at the end of the toe are carried by a front arm 18 mounted for swinging movement lengthwise of the shoe, the overlaying means comprising toe embracing wipers which gather and wipe the margin of the upper inwardly round the end and along the sides of the toe. At the opposite sides of the forepart are side arms 20 which are mounted to swing laterally of the shoe and carry the devices for fastening the upper at the sides of the toe, these arms being operative in their inward movement to close the toe wipers inwardly over the shoe as the wipers are advancing lengthwise of the shoe. Although the invention is not limited in respect to the character of the overwiping means, the machine herein shown, in common with the machine of the Ashton patent, comprises wipers which are mounted on a wiper holder 22 supported on the arm 18 in such manner as to permit it to be manipulated by the operator while the machine is at rest prior to the final stage of the cycle for advancing and positioning the wipers in engagement with the shoe preparatory to the overwiping operation. The construction shown also includes well known means whereby the toe gripper 2 may be released manually from engagement with the upper by a lever 24 as the wipers are thus positioned and before the machine is started in the final stage of the cycle, although the invention is likewise not dependent upon this particular manner of control of the toe gripper.

The side grippers 4 have an overdraw movement as the wipers are closed inwardly and are finely tripped automatically by engagement of the side arms with tripping devices 26 for releasing the margin of the upper. It will be understood that the front arm 18 in its operative movement picks up the wiper holder 22 and forces the wipers rearwardly over the shoe for a distance determined by engagement of a pad 28 on the wiper holder with the end face of the shoe.

The toe wipers herein illustrated are similar in construction to wipers heretofore provided, and comprise a pair of end wiper plates 30 mounted on a carrier plate 32 for closing movement about a common pivot 34 located substantially midway between the opposite sides of the toe, and a pair of additional wiper plates 36, which may be termed side wiper plates, mounted on the carrier plate 10 32 to swing inwardly under the end plates about pivots 38 on the plate 32 located at opposite sides of the central pivot 34. It will be understood that the side plates 36 are engaged and forced inwardly by members 15 on the side arms 20, and they carry pins 40 which engage the end plates 30 and close them also inwardly. Springs 42 connected to pins on the side plates and on the carrier plate return the side plates and the 20 end plates to open position. It will be noted by reference to Fig. 3 that the side plates 36 are beveled on their lower over-wiping faces to assist in guiding them inwardly over the edge of the shoe bottom, 25 and it will also be noted in said figure that the side arms 20, similarly to prior machines, carry additional overlaying members 44, which operate at the rear of the plates 36 and assist in overlaying and holding the 30 margin of the upper for the fastening operation.

The means for limiting the inward movement of the side arms in the machine herein shown comprises stop screws 46 which are 35 mounted in members 48 fast on the lower ends of the arms and are arranged to engage abutment members 50 on the clamp arms 16. It will be understood that this mechanism determines the distance from the 40 sides of the toe at which the side tacks are driven, as will be evident by reference to Fig. 5, and that by adjustment of the screws 46 the distance of the tacks from the edge of the shoe bottom may be varied. For closing the wipers inwardly, the side arms 20 carry wiper closing blocks or plates 52, (Fig. 5) which engage the wipers 36 and are 45 adjustable inwardly or outwardly by means of adjusting screws 54 to determine additionally the extent of closing movement of the wipers and their relation to the tacking instrumentalities. For one of the purposes of the present invention the wiper closing members 52 are each provided with a wedge 55 face 56 for engagement with the wipers to wedge them downwardly toward the plane of the shoe bottom as they are forced inwardly over the shoe to increase the over-wiping and upper holding pressure.

60 The machine herein shown, as will be evident by reference to Fig. 9, is constructed to drive three lasting tacks at the end of the toe and three additional lasting tacks at each side of the toe, although the number of the tacks may be varied as desired. The tack-

ing means provided is generally similar to the means illustrated in said prior Ashton patent, comprising on each of the front and side arms a driver bar 58 connected at its lower end to drivers 60 and operated by a spring arm 62. The tack drivers 60 of the different tackers are mounted on tacker plates 64 which carry tack holders 66, one of these tacker plates on each side arm 20 being fixed in relation to the arm and the 75 other two plates being yieldingly mounted to permit them to be positioned automatically in relation to the shoe by engagement of blocks 68 which they carry with the outer edges of the wipers. On the front arm 18 80 the central tacker plate 64 is likewise positioned in fixed relation to the arm, while the plates at each side of the central plate, with their associated tack holders and drivers, are adjustable lengthwise of the shoe. For the purpose of such adjustment each side plate in the present machine carries a threaded rod 70 which extends through a block 72 mounted in fixed relation to the arm 18 and carries an adjusting nut 74 in bearing engagement with said block. A spring 76 between the block 72 and a lug on the plate 64, to which the rod 70 is connected, co-operates with the nut 74 in the adjustment of the tacker while permitting the tacker to yield 95 in response to any abnormal resistance.

The means for swinging the front and side arms inwardly, as in prior machines of the same general type, comprises a rack bar 78 (Fig. 6) which at its front end is connected to the arm 18 by means of yieldable spring-pressed wedge blocks 80 in engagement with inclined faces on plates 82 which are guided for upward and downward movements along the arm 18. The rack bar 78 is connected to 100 the side arms through gear segments 84 and rack slides 86 which carry spring-pressed wedge blocks 88 in engagement with inclined faces on slides 90 connected to the arms 20 in such manner as to permit them to move 105 upwardly and downwardly along the arms. It will be understood that as the rack bar 78 is moved rearwardly, the front and side arms are moved yieldingly inward by the action of the wedge blocks 80 and 88 to the limits of movement determined by engagement of the pad 28 with the end of the shoe and of the stop screws 46 with the members 50. It 110 will also be understood that it is by continued movement of the rack bar 78 and the slides 86 that the driver bars 58 are released to the action of their spring arms 62. For the purpose of such control of the driver bars, the member 78 is arranged to project under the lower end of a plate 92 on the front driver bar 58, and the slides 86 have members projecting under blocks 94 on the side driver bars 58. By this means the driver bars are supported in upraised position until the front and side arms have been 115 120 125 130

4

moved inwardly to the limits determined as above described, whereupon continued movement of the member 78 and the connected slides 86 serves to release the driver bars 5 and to cause the tacks to be driven. In this operation the wedge blocks 80 and 88 slip over, and it may be past, the inclines on the members 82 and 90 with which they co-operate. The rack bar 78 and the connections 10 between this bar and the side arms are mounted on a support 96 which has a vertical swinging movement in time relation to the return outward movement of the rack bar after the tack driving operation to pick 15 up the driver bars and raise them again during the outward swinging movement of the arms.

For further purposes of the present invention the front and side arms 18 and 20 are 20 mounted for bodily downward movement with the wipers and tackers after they have arrived at their limits of inward movement. For this purpose the arms have secured to 25 their upper ends circular bearing members 98 which have slots extending lengthwise of the arms to co-operate with guide blocks 100 mounted on pivots 102 which are fast on the frame. The arms are normally held in upraised position by the action of the driver 30 bars 58, the front arm having secured thereto a plate 104 which is engaged and upheld by the member 92 on the driver bar, and the side arms (Fig. 3) having fast thereon plates 106 which are engaged and upheld by plates 35 108 on the side driver bars. It will thus be evident that when the driver bars are released for driving the tacks the arms also are released and permitted to move downwardly. By such movement of the arms the 40 wipers are forced down firmly upon the margin of the upper, the side arms acting upon the wipers through the wedge faces 56, and the tack holders 66 also are moved downwardly toward the bottom of the shoe to decrease 45 the space through which the tacks must be driven. The downward pressure of the arms is further increased by the drivers 58, the heads 110 of which engage the upper ends of the arms to limit movement of 50 the drivers, the arms thus being subjected to the force applied by the driver operating arms 62. Downward movement of the arms may be limited by bearing shoulders 112 on the frame which co-operate with curved 55 flanges 114 on the arms, such provision for limiting the movement of the arms being particularly useful in case the machine is operated in the absence of any shoe.

As hereinbefore explained, the release of 60 the driver bars is accompanied by such movements of the wedge blocks 80 and 88 as to decease their effectiveness in holding the front and side arms at their inner limits of movement during the tack driving operation. As further insurance that the arms

and consequently the wipers will be held from outward movement during the driving of the tacks and during the downward movement of the arms to apply increased pressure to the wipers, the machine is further 70 provided, for purposes of this invention, with supplemental means to apply inward pressure to the arms. To this end, each of the rack slides 86 associated with the side arms has an extension 116 on which is secured 75 a socket member 118 provided with a plunger 120 which is pressed inwardly by a spring 122 and through a bearing member 124 presses inwardly on the outer face of the side arm. On the front arm 18 there is 80 pivoted a plate 126 which carries a spring-pressed plunger 128 similar to the plungers 120 and engaging the front or outer face of the arm. Secured to the plate 126 is a curved bearing member 130, the front face 85 of which is engaged by a roll 132 carried by an extension member 134 which projects forwardly from the rack bar 78. It will be evident that with this construction the continued movement of the rack bar 78 and the connected slides 86 after the arms 18 and 20 have arrived at their inner limits of movement, serves to force the spring plungers 120 and 128 with increased pressure against the 90 outer faces of the respective arms and thus 95 to assist in holding the arms against outward movement until the tacks are driven. In order to permit a substantial increase of pressure to be thus applied to the arms, the members 92 and 94 on the driver bars 100 whereby the bars are normally upheld are made wider than usual, to increase the extent of movement of the rack bar 78 and its connected slides which is necessary in order to trip or release the driver bars. The 105 curved member 130 serves to maintain an operative connection between the rack bar 78 and the plunger supporting plate 126 during the swinging movement of the bar 78 in the return of the parts to starting position. 110

The above described controlling means for the front and side arms insures that the wipers will be maintained in position to apply their full pressure to the upper in the 115 upper fastening operation, such control of the arms being particularly advantageous in an organization such as illustrated where there is a relative movement between the arms and the shoe to increase the wiper pressure after the wipers have been closed inwardly over the shoe. The provision of supplemental means to assist in imparting inward movement to the arms has also a further advantage in the insurance afforded 120 against premature release of the tack drivers in the event of unusual resistance to the inward movement of the arms, for example when the machine is operating on heavy 125 shoes. It will be evident that under such 130

conditions the spring plungers 120 and 128, which co-operate with the wedge blocks in maintaining an operative connection between the arms and the bar 78, insure that 5 the arms will be forced to their inner limits of movement prior to such slipping movement of the wedge blocks as to effect the release of the drivers. While the supplemental controlling means is herein illustrated in its application to the front arm 10 and the side arms, it will be understood that the invention is not limited to an organization in which such means is applied to all the arms.

15 To summarize briefly the operation of the machine, it may be stated that after the machine has come to a stop with the upper held under tension and after any of the usual 20 adjustments which may be necessary have been made, the operator advances the wiper holder 22 and positions the wipers in proper relation to the shoe, at the same time releasing the toe gripper. The machine is then 25 started again and the wipers are advanced and closed inwardly over the shoe as hereinbefore explained, the wedge faces 56 on the side arm blocks 52 acting to force the wipers toward the plane of the shoe bottom as they are moved inwardly. After the front 30 and side arms and their associated wipers and tackers have arrived at their inner limits of movement, the tack driver bars are tripped or released by continued movement of the mechanism which acts to swing the 35 arms inwardly, additional inward pressure being applied to the arms through the spring plungers 120 and 128 prior to and during the driving of the tacks. As the driver bars are released to drive the tacks, the front and side arms also are released 40 and are moved bodily toward the plane of the shoe bottom by gravity and by the friction of the driver bars, being finally engaged and forcibly depressed by the heads of the 45 driver bars, thereby forcing the wipers more firmly against the margin of the upper and moving the tack holders into closer proximity to the bottom of the shoe. The drivers have a movement of sufficient extent to drive 50 the several lasting tacks to their final positions in the shoe, clenching the ends of the tacks on the metal plate *a* with which the last is provided for McKay shoe work, as 55 illustrated in Fig. 5. The parts are then returned to their starting positions, the arms 18 and 20 being upraised again by the action of the driver bars.

60 While the invention has been described herein by reference to McKay shoe work, it will be understood that many of the novel features of the illustrative machine are not limited to the manufacture of that particular type of shoe but are of general utility in the manufacture of shoes of various kinds. 65 It will also be understood that in many of

its features the invention is not dependent upon the use of a particular form of upper securing fastening, and the term "tack" and similar terms are accordingly used herein as convenient terms of designation for a general type of fastening and not by way of limitation to a particular form of fastening. 70

Having described the invention, what I claim as new and desire to secure by Letters Patent of the United States is:— 75

1. A machine for pulling-over and lasting McKay shoes having, in combination, means for pulling an upper over a last, toe embracing wipers and means for operating them to gather and wipe inwardly the margin of the upper about the toe of the last with substantial pressure upon the insole, and upper fastening mechanism constructed to drive a plurality of permanent lasting tacks through the margin of the upper and the insole round the end and along the sides of the toe as far into the shoe as permitted by the shoe materials and to clench said tacks on the anvil plate of the last. 80

2. A machine for pulling-over and lasting McKay shoes having, in combination, means for pulling an upper over a last, toe embracing wipers for gathering and wiping inwardly the margin of the upper about the toe of the shoe, means for closing said wipers inwardly over the shoe, mechanism for effecting relative movement of said wipers and the shoe in a direction transverse to the plane of the shoe bottom for pressing the margin of the upper upon the insole, and upper fastening mechanism constructed to drive a plurality of lasting tacks through the margin of the upper and the insole round the end and along the sides of the toe and to clench said tacks on the anvil plate of the last. 95

3. A machine for pulling-over and lasting McKay shoes having, in combination, means for pulling an upper over a last, toe embracing wipers for gathering and wiping inwardly the margin of the upper about the toe of the shoe, operating means for closing said wipers inwardly over the shoe and for simultaneously forcing them toward the plane of the shoe bottom to increase their pressure on the margin of the upper, and upper fastening mechanism constructed to drive a plurality of lasting tacks through the margin of the upper and the insole round the end and along the sides of the toe and to clench said tacks on the anvil plate of the last. 105

4. A machine for pulling-over and lasting McKay shoes having, in combination, means for pulling an upper over a last, toe embracing wipers and means for closing them over the shoe to gather and wipe inwardly the margin of the upper about the toe of the shoe, mechanism automatically operative in the inward movement of said wipers over the 110 120 125 130

- 6 shoe to force them toward the plane of the shoe bottom for increasing the overwiping pressure on the upper, additional means for effecting relative movement of said wipers and the shoe in a direction transverse to the plane of the shoe bottom to apply further pressure to the upper after the wipers have been closed inwardly, and upper fastening mechanism constructed to drive a plurality of lasting tacks through the upper and the insole round the end and along the sides of the toe and to clench said tacks on the anvil plate of the last.
- 5 7. A machine for pulling-over and lasting McKay shoes having, in combination, power-operated upper pulling means automatically controlled to come to a stop with the upper held under tension, toe embracing wipers and means for closing them over the shoe upon 15 a subsequent starting of the machine to gather and wipe inwardly the margin of the upper about the toe of the shoe, means automatically operative in time relation to the closing of the wipers to effect a relative 20 movement of the shoe and the wipers in a direction transverse to the plane of the shoe bottom for increasing the pressure on the margin of the upper, and means operative after the wipers have completed their inward movement to drive a plurality of lasting tacks through the upper and the insole round the end and along the sides of the toe and to clench said tacks on the anvil plate of the last.
- 25 8. A machine for pulling-over and lasting McKay shoes having, in combination, power-operated upper pulling means automatically controlled to come to a stop with the upper held under tension, toe embracing wipers and means for operating them upon a subsequent starting of the machine to gather and wipe inwardly the margin of the upper about the toe of the shoe with substantial pressure upon the insole, and upper fastening mechanism automatically operative in time relation to the wipers to drive a plurality of permanent lasting tacks through the margin of the upper and the insole round the end and along the sides of the toe 30 as far into the shoe as permitted by the shoe materials and to clench said tacks on the anvil plate of the last.
- 35 9. In a machine for lasting the toes of McKay shoes, the combination with shoe positioning means, of toe embracing wipers for gathering and wiping the margin of the upper inwardly about the toe of the shoe, upper fastening means constructed to drive a plurality of permanent lasting tacks round the end and along the sides of the toe as far into the shoe as permitted by the shoe materials and to clench said tacks on the anvil plate of the last, and power means for operating said wipers and upper fastening means in time relation.
- 40 10. In a machine for lasting the toes of McKay shoes, the combination with shoe positioning means, of toe embracing wipers for gathering and wiping the margin of the upper inwardly about the toe of the shoe, upper fastening means comprising a plurality of tackers constructed to drive lasting tacks round the end and along the sides of the toe and to clench said tacks on the anvil plate of the last, and power means for operating said wipers and tackers and for effecting in time relation to the operation of the wipers a relative movement of the shoe and the wipers in a direction transverse to the plane of the shoe bottom for increasing the pressure on the upper.
- 45 11. In a machine for lasting the toes of McKay shoes, the combination with shoe positioning means, of toe embracing wipers and means for closing them inwardly about the toe to gather and wipe the margin of the upper over the insole, mechanism automatically operative in time relation to the closing of the wipers to effect a relative movement of the shoe and the wipers transversely of the plane of the shoe bottom to increase the pressure on the upper, and means for fastening the upper in lasted position comprising a plurality of tackers and mechanism for operating them to drive lasting tacks round the end and along the sides of the toe and to clench said tacks on the anvil plate of the last.
- 50 12. In a machine for lasting the toes of McKay shoes, the combination with shoe positioning means, of toe embracing wipers

- for gathering and wiping inwardly the margin of the upper about the toe of the shoe, upper fastening mechanism comprising a plurality of tackers for driving lasting tacks 5 round the end and along the sides of the toe and for clenching said tacks on the anvil plate of the last, and operating means for closing said wipers inwardly over the shoe and for moving said wipers and tackers in a 10 direction transverse to the plane of the shoe bottom to increase the pressure on the margin of the upper and to position the tackers in close relation to said plane for the tacking operation. 15
13. In an end lasting machine, the combination with shoe positioning means, of end embracing wipers for gathering and wiping the margin of the upper inwardly about an end of the shoe, means for closing said wipers inwardly over the shoe, means for moving the wipers toward the plane of the shoe bottom to increase their pressure on the margin of the upper after they have completed their inward movement, and upper fastening means 20 constructed to drive a plurality of fastenings transversely of the plane of the shoe bottom round the end and along the sides of the end portion of the shoe to secure the upper in lasted position. 25
14. In an end lasting machine, the combination with shoe positioning means, of end embracing wipers for gathering and wiping the margin of the upper inwardly about an end of the shoe, operating means for closing 30 the wipers inwardly over the shoe, mechanism automatically operative in the closing of the wipers to effect relative movement of the shoe and the wipers in a direction transverse to the plane of the shoe bottom to increase the overwiping pressure, additional means for effecting a similar relative movement of the shoe and the wipers after the wipers have completed their inward movement further to increase the pressure on the margin 35 of the upper, and means for fastening the upper in lasted position. 40
15. In an end lasting machine, the combination with shoe positioning means, of end embracing wipers for gathering and wiping the margin of the upper inwardly about an end of the shoe, operating means for closing the wipers inwardly over the shoe, mechanism automatically operative in time relation to the closing of the wipers to impart 45 to the wipers successive movements in a direction transverse to the plane of the shoe bottom for increasing the pressure on the margin of the upper, and means for fastening the upper in lasted position. 50
16. In an end lasting machine, the combination with shoe positioning means, of end embracing wipers for gathering and wiping the margin of the upper inwardly about an end of the shoe, means for closing said wipers inwardly over the shoe, upper fastening 55
- means constructed to drive a plurality of upper securing fastenings transversely of the plane of the shoe bottom round the end and along the sides of the end portion of the shoe, and means for moving said wipers and fastening means toward the plane of the shoe bottom to increase the pressure of the wipers on the upper and to position said fastening means in close relation to said plane for the fastening operation. 60
17. In an end lasting machine, the combination with shoe positioning means, of end embracing wipers for gathering and wiping the margin of the upper inwardly about an end of the shoe, a plurality of tackers movable inwardly over the shoe bottom into position for driving upper fastening tacks round the end and along the sides of the end portion of the shoe, mechanism automatically operative in the closing of the wipers to move them transversely of the plane of the shoe bottom for increasing the overwiping pressure, and additional means operative after the wipers and the tackers have been closed inwardly to move said wipers and tackers in a direction further to increase the pressure on the upper and to position the tackers in close relation to the plane of the shoe bottom. 65
18. In an end lasting machine, the combination with shoe positioning means, of end embracing wipers for gathering and wiping the margin of the upper inwardly about an end of the shoe, operating means for closing 70 said wipers inwardly over the shoe and for imparting to them in their closing movement a movement transversely of the plane of the shoe bottom to increase the overwiping pressure, and additional means for imparting a further movement to the wipers transversely of said plane after they have completed their inward movement further to increase their pressure on the upper. 75
19. In an end lasting machine, the combination with shoe positioning means, of end embracing wipers for gathering and wiping the margin of the upper inwardly about an end of the shoe, and wiper closing devices mounted independently of the wipers and movable laterally of the shoe at its opposite 80 sides to close the wipers over the shoe, said devices being constructed to force the wipers toward the plane of the shoe bottom as they are moved inwardly over the shoe to increase 85 their pressure on the upper. 90
20. In an end lasting machine, the combination with shoe positioning means, of end embracing wipers mounted for closing movement inwardly over the shoe, and members movable laterally of the shoe to close the 95 wipers inwardly, said members being movable in wedging engagement with the wipers to force the wipers toward the plane of the shoe bottom in their closing movement. 100
21. In an end lasting machine, the combi- 105

nation with shoe positioning means, of end embracing wipers mounted for advancing movement lengthwise of the shoe and for closing movement inwardly over the shoe, 5 and members movable laterally of the shoe to close the wipers inwardly, said members having wedge faces thereon inclined to the plane of the shoe bottom for engaging the wipers and wedging them toward said plane 10 to increase the overwiping pressure as the wipers are moved inwardly.

22. In an end lasting machine, the combination with shoe positioning means, of end embracing wipers mounted for advancing 15 movement lengthwise of the shoe and for closing movement inwardly over the shoe, closing devices mounted independently of said wipers and movable laterally of the shoe to close the wipers inwardly, said closing devices being constructed to force the wipers toward the plane of the shoe bottom as they are moved inwardly, and means for moving said devices in a direction transverse to the plane of the shoe bottom after the inward movement of the wipers has been substantially completed to increase the pressure of the wipers on the shoe.

23. In an end lasting machine, the combination with shoe positioning means, of end embracing wipers mounted for advancing movement lengthwise of the shoe and for closing movement inwardly over the shoe, members movable laterally of the shoe for closing the wipers inwardly, said members 35 having wedge faces thereon for engaging the wipers and forcing them toward the plane of the shoe bottom as they are closed inwardly, and means for moving said members transversely of said plane after the wipers have substantially completed their inward movement to apply further pressure to the wipers through said wedge faces for compressing the overwiped margin of the upper.

24. In an end lasting machine, the combination with shoe positioning means, of end embracing wipers mounted for advancing movement lengthwise of the shoe and for closing movement inwardly over the shoe, members mounted independently of the 45 wipers and movable laterally of the shoe for closing the wipers inwardly, means for moving said members transversely of the plane of the shoe bottom after the wipers have substantially completed their inward movement to increase the pressure of the wipers on the upper, and means for fastening the upper in lasted position.

25. In an end lasting machine, the combination with shoe positioning means, of end embracing wipers for gathering and wiping the margin of the upper inwardly about an end of the shoe, a wiper support movable to advance said wipers lengthwise of the shoe, wiper closing members mounted independently of the wipers and movable laterally

of the shoe to close the wipers inwardly, means for moving said wiper support and members transversely of the plane of the shoe bottom to increase the pressure of the wipers on the upper, and upper fastening devices carried by said support and members for fastening the upper in lasted position.

26. In an end lasting machine, the combination with shoe positioning means, of end 75 embracing wipers for gathering and wiping the margin of the upper inwardly about an end of the shoe, a wiper support movable to advance the wipers lengthwise of the shoe, wiper closing members movable laterally of the shoe to close the wipers inwardly and having means thereon for forcing the wipers toward the plane of the shoe bottom during their inward movement, and means for moving said wiper support and members transversely of the plane of the shoe bottom after the advancing and closing movement of the wipers has been substantially completed to increase the pressure on the margin of the upper.

27. In an end lasting machine, the combination with shoe positioning means, of end embracing wipers for gathering and wiping the margin of the upper inwardly about an end of the shoe, means for driving fastenings transversely of the plane of the shoe bottom for securing the upper in lasted position, and mechanism controlled by said driving means for imparting to the wipers a movement transversely of the plane of the shoe bottom to increase the pressure of the wipers on the upper.

28. In an end lasting machine, the combination with shoe positioning means, of end embracing wipers for gathering and wiping the margin of the upper inwardly about an end of the shoe, tack driving members movable inwardly at the end and the opposite sides of the end portion of the shoe into tack driving position, and mechanism controlled by said tack driving members for moving the wipers transversely of the plane of the shoe bottom to increase their pressure on the margin of the upper.

29. In an end lasting machine, the combination with shoe positioning means, of end embracing wipers for gathering and wiping the margin of the upper inwardly about an end of the shoe, members movable lengthwise and laterally of the shoe for advancing and closing the wipers respectively, said members having means thereon for driving fastenings to secure the margin of the upper in lasted position, and mechanism controlled by said driving means to cause said members to move transversely of the plane of the shoe bottom to increase the pressure of the wipers on the upper.

30. In an end lasting machine, the combination with shoe positioning means, of end

- embracing wipers for gathering and wiping the margin of the upper inwardly about an end of the shoe, a wiper support movable to advance said wipers lengthwise of the shoe, 5 and means on said wiper support for driving fastenings to secure the upper in lasted position, said driving means being constructed to move said wiper support transversely of the plane of the shoe bottom in the driving operation to increase the pressure of the wipers on the upper.
31. In an end lasting machine, the combination with shoe positioning means, of end embracing wipers for gathering and wiping the margin of the upper inwardly about an end of the shoe, members movable lengthwise and laterally of the shoe for advancing and closing the wipers respectively, upper fastening means comprising tack driver bars associated with said members for driving tacks to fasten the upper in lasted position, and means on said driver bars for moving said members transversely of the plane of the shoe bottom in the tack driving operation to increase the pressure of the wipers on the upper.
32. In an end lasting machine, the combination with shoe positioning means, of end embracing wipers for gathering and wiping the margin of the upper inwardly about an end of the shoe, a support for said wipers, tack driving means, and mechanism for upholding said wiper support automatically operative to release the support and permit the wipers to move toward the plane of the shoe bottom before the tacks are driven.
33. In an end lasting machine, the combination with shoe positioning means, of end embracing wipers for gathering and wiping the margin of the upper inwardly about an end of the shoe, a support for said wipers, tack driving means, and mechanism controlled by said tack driving means to cause the wiper support to move the wipers toward and from the plane of the shoe bottom.
34. In an end lasting machine, the combination with shoe positioning means, of end embracing wipers for gathering and wiping the margin of the upper inwardly about an end of the shoe, a support for said wipers, a tack driver bar, and means on said tack driver bar for upholding the wiper support and for releasing said support in the tack driving operation to permit the wipers to be forced toward the plane of the shoe bottom.
35. In an end lasting machine, the combination with shoe positioning means, of end embracing wipers for gathering and wiping the margin of the upper inwardly about an end of the shoe, a support for said wipers, tack driving means, mechanism controlled by said tack driving means for upholding the wiper support and for releasing it in time relation to the tack driving operation, and means for rendering said tack driving
- means effective in its operative movement to move the wiper support in a direction to increase the pressure of the wipers on the shoe.
36. In an end lasting machine, the combination with shoe positioning means, of end embracing wipers for gathering and wiping the margin of the upper inwardly about an end of the shoe, a support for said wipers, tacking mechanism on said wiper support, and means automatically operative in time relation to the closing of the wipers to cause said support to move transversely of the plane of the shoe bottom for increasing the wiper pressure and positioning the tacking mechanism relatively to the bottom of the shoe.
37. In an end lasting machine, the combination with shoe positioning means, of end embracing wipers for gathering and wiping the margin of the upper inwardly about an end of the shoe, a support for said wipers, tack holders and tack driving means on said wiper support, and mechanism controlled by said tack driving means to cause said support to move transversely of the plane of the shoe bottom for increasing the wiper pressure and positioning the tack holders relatively to the bottom of the shoe.
38. In an end lasting machine, the combination with shoe positioning means, of end embracing wipers for gathering and wiping the margin of the upper inwardly about an end of the shoe, tacking devices for the opposite sides of the end of the shoe having members arranged for engagement with the wipers, and means for moving said tacking devices transversely of the plane of the shoe bottom to position them relatively to said plane by engagement with the wipers.
39. In a machine of the class described, the combination with shoe positioning means, of an overlaying member movable inwardly over the bottom of the shoe, and an operating member mounted independently of said overlaying member and movable inwardly in substantially the same direction as the overlaying member in wedging engagement with the overlaying member to force it inwardly over the bottom of the shoe and also toward the plane of the shoe bottom.
40. In a machine of the class described, the combination with shoe positioning means, of an overlaying member movable inwardly over the bottom of the shoe, and an operating member mounted independently of said overlaying member and movable in a direction transverse to the height of the shoe to force said member inwardly over the shoe, said operating member having thereon a wedge face inclined to the plane of the shoe bottom to wedge the overlaying member toward said plane as it is moved inwardly.
41. In a machine of the class described, the combination with shoe positioning means, of

a wiper movable inwardly over the bottom of the shoe, a member mounted independently of said wiper and movable to force the wiper inwardly, said member being constructed and arranged to force the wiper also toward the plane of the shoe bottom as it is moved inwardly, and means to cause said member to move transversely of said plane after the inward movement of the wiper 10 has been substantially completed to increase the pressure of the wiper on the shoe.

42. In a machine of the class described, the combination with shoe positioning means, of a wiper movable inwardly over the bottom 15 of the shoe, a member movable to force the wiper inwardly over the shoe, said member having a wedge face thereon for wedging the wiper toward the plane of the shoe bottom as it is forced inwardly, and means for moving said member transversely of the plane of the shoe bottom after the inward movement of the wiper has been substantially completed to increase the pressure of the wiper 20 on the shoe.

43. In a machine of the class described, the combination with shoe positioning means, of a wiper movable inwardly over the bottom of the shoe, a member mounted independently of said wiper for moving the wiper inwardly, tack driving means associated with said member for fastening the upper in overwiped position, and mechanism controlled by said tack driving means for moving said member transversely of the 30 plane of the shoe bottom to increase the pressure of the wiper on the upper.

44. In a machine of the class described, the combination with shoe positioning means, of a wiper support, a wiper on said support, 40 upper fastening means comprising a tack holder also carried by said support, and means automatically operative to cause said support to move transversely of the plane of the shoe bottom before the tack is driven for increasing the wiper pressure and positioning the tack holder relatively to said plane.

45. In a machine of the class described, the combination with shoe positioning 50 means, of a wiper support movable inwardly toward the shoe and also movable transversely of the plane of the shoe bottom, a wiper on said support, upper fastening means comprising a tack holder also carried by said support, and controlling means for said support automatically operative to release it and permit it to move transversely of the plane of the shoe bottom to increase the wiper pressure and position the tack holder 55 relatively to said plane before the tack is driven.

46. In a machine of the class described, the combination with shoe positioning 60 means, of a wiper movable inwardly over the bottom of the shoe, and tacking mechanism

mounted independently of the wiper for positioning movement transversely of the plane of the shoe bottom and having means for engaging the wiper to determine the relation of the mechanism to said plane. 70

47. A machine of the class described having, in combination, means for pulling an upper over a last, toe embracing wipers for gathering and wiping the margin of the upper inwardly about the toe 75 of the shoe, means for moving said wipers inwardly over the shoe and for moving them also in a direction transverse to the plane of the shoe bottom after they have completed their inward movement to increase their 80 pressure on the upper, and means for driving a plurality of upper securing fastenings transversely of the plane of the shoe bottom round the end and along the sides of the toe to fasten the upper in lasted position. 85

48. A machine of the class described having, in combination, means for pulling an upper over a last, toe embracing wipers for gathering and wiping the margin of the upper inwardly about the toe of the shoe, 90 means for driving a plurality of upper securing fastenings transversely of the plane of the shoe bottom to fasten the upper in lasted position, and mechanism controlled by said driving means for forcing the wipers toward 95 the plane of the shoe bottom to increase their pressure on the upper.

49. A machine of the class described having, in combination, means for pulling an upper over a last, toe embracing wipers for 100 gathering and wiping the margin of the upper inwardly about the toe of the last, means automatically operative to effect successive relative movements of the shoe and the wipers transversely of the plane of the 105 shoe bottom for increasing the wiper pressure, and means for fastening the upper in lasted position.

50. A machine of the class described having, in combination, means for pulling an upper over a last, toe embracing wipers for 110 gathering and wiping the margin of the upper inwardly about the toe of the last, means for closing said wipers inwardly and for forcing them toward the plane of the 115 shoe bottom in their closing movement, additional means for moving the wipers subsequently toward said plane to increase the wiper pressure, and means for fastening the upper in lasted position. 120

51. A machine of the class described having, in combination, means for pulling an upper over a last, toe embracing wipers for gathering and wiping the margin of the upper inwardly about the toe of the shoe, 125 upper fastening means comprising tack holders and drivers for fastening the margin of the upper in lasted position, and means automatically operative in time relation to the tacking operation to cause said 130

tack holders to move toward the plane of the shoe bottom.

52. A machine of the class described having, in combination, means for pulling an upper over a last, toe embracing wipers for gathering and wiping the margin of the upper inwardly about the toe of the shoe, upper fastening means comprising tack holders and drivers for fastening the margin of the upper in lasted position, and means controlled by said drivers to cause the tack holders to move toward the plane of the shoe bottom for the tack driving operation.

53. A machine of the class described having, in combination, means for pulling an upper over a last, toe embracing wipers for gathering and wiping the margin of the upper inwardly about the toe of the shoe, and front and side arms movable respectively lengthwise and laterally of the shoe to operate said wipers, said front and side arms being movable bodily in a direction transverse to the plane of the shoe bottom to increase the pressure of the wipers on the upper.

54. A machine of the class described having, in combination, means for pulling an upper over a last, toe embracing wipers for gathering and wiping the margin of the upper inwardly about the toe of the shoe, front and side arms movable respectively lengthwise and laterally of the shoe to operate said wipers, and means automatically operative to move said arms bodily in a direction transverse to the plane of the shoe bottom to increase the pressure of the wipers on the upper.

55. A machine of the class described having, in combination, means for pulling an upper over a last, toe embracing wipers for gathering and wiping the margin of the upper inwardly about the toe of the shoe, front and side arms movable respectively lengthwise and laterally of the shoe for operating said wipers, said arms having upper fastening devices thereon, and means controlled by said upper fastening devices to cause the arms to move transversely of the plane of the shoe bottom for applying pressure to the wipers.

56. A machine of the class described having, in combination, means for pulling an upper over a last, toe embracing wipers for gathering and wiping the margin of the upper inwardly about the toe of the shoe, front and side arms movable respectively lengthwise and laterally of the shoe to operate the wipers, said arms being movable also transversely of the plane of the shoe bottom, and upper fastening devices comprising tack driver bars arranged to uphold said arms prior to the tack driving operation and to release them to permit them to move toward the plane of the shoe bottom as the tacks are driven.

57. A machine of the class described having, in combination, means for pulling an upper over a last, toe embracing wipers for gathering and wiping the margin of the upper inwardly about the toe of the shoe, front and side arms movable respectively lengthwise and laterally of the shoe to operate said wipers, said arms being movable also transversely of the plane of the shoe bottom, upper fastening devices comprising driver bars on said arms, means on said driver bars for upholding the arms prior to the tack driving operation and for releasing them as the tacks are driven, and means on said driver bars for forcing the arms toward the plane of the shoe bottom to increase the pressure of the wipers on the upper.

58. A machine of the class described, having, in combination, means for pulling an upper over a last, toe embracing wipers for gathering and wiping the margin of the upper inwardly about the toe of the shoe, a front arm movable lengthwise of the shoe to advance said wipers, side arms movable laterally of the shoe to force the wipers inwardly, and means on said side arms for wedging the wipers toward the plane of the shoe bottom as they are forced inwardly.

59. A machine of the class described having, in combination, means for pulling an upper over a last, toe embracing wipers for gathering and wiping the margin of the upper inwardly about the toe of the shoe, side arms movable laterally of the shoe and having means for engaging the wipers, and means for moving said arms bodily in a direction transverse to the plane of the shoe bottom to apply pressure to the wipers.

60. A machine of the class described having, in combination, means for pulling an upper over a last, toe embracing wipers for gathering and wiping the margin of the upper inwardly about the toe of the shoe, side arms movable laterally of the shoe and having tackers mounted thereon, said arms having also means for engaging the wipers, and means for moving said arms bodily in a direction transverse to the plane of the shoe bottom to apply pressure to the wipers and to position the tackers relatively to said plane.

61. A machine of the class described having, in combination, means for pulling an upper over a last, toe embracing wipers for wiping the margin of the upper inwardly about the toe of the shoe, a front arm carrying said wipers and mounted for swinging movement lengthwise of the shoe, said arm being also movable lengthwise in directions transverse to the plane of the shoe bottom, means carried by said arm for driving tacks transversely of the plane of the shoe bottom to fasten the upper in overwiped position, and mechanism controlled by said tack

120

125

130

driving means to cause the arm to move lengthwise in a direction to increase the pressure of the wipers on the shoe.

62. A machine of the class described having, in combination, means for pulling an upper over a last, toe embracing wipers for wiping the margin of the upper inwardly about the toe of the shoe, a front arm carrying said wipers and mounted for swinging movement lengthwise of the shoe, said arm being also movable lengthwise in directions transverse to the plane of the shoe bottom, tacking mechanism comprising a driver bar carried by said arm, means automatically operative after the wipers have been closed inwardly to release the arm and permit it to move in a direction to force the wipers toward the plane of the shoe bottom, and means operated by said driver bar for moving the arm in said direction to increase the wiper pressure.

63. In a machine of the class described, the combination with means for pulling an upper over a last, of front and side arms mounted to swing toward and from the shoe and movable also in directions transverse to the plane of the shoe bottom, overlaying and fastening devices carried by said arms, and controlling means for said arms automatically operative to cause them to move transversely of said plane after their movement toward the shoe has been substantially completed.

64. In a machine of the class described, the combination with means for pulling an upper over a last, of overlaying means for the margin of the upper comprising an arm supported for swinging movement toward and from the shoe, said arm having a slotted connection with its support adjacent to its axis of swinging movement to permit it to move lengthwise in directions transverse to the plane of the shoe bottom, and means for controlling said lengthwise movements of the arm.

65. In a machine of the class described, the combination with means for pulling an upper over a last, of overlaying means for the margin of the upper comprising an arm supported for swinging movement toward and from the shoe, said arm having a slotted connection with its support adjacent to its axis of swinging movement to permit it to move lengthwise in directions transverse to the plane of the shoe bottom, upper fastening mechanism carried by said arm, and means for controlling the lengthwise movement of said arm by the movement of said upper fastening mechanism.

66. In a machine of the class described, the combination with grippers for pulling an upper over a last at the toe and at opposite sides of the forepart, of upper fastening means comprising tack holders and drivers arranged to drive upper fastening tacks at

the end and the sides of the forepart and movable inwardly with substantial clearance between the tack holders and the bottom of the shoe, and controlling means for said tack holders automatically operative to cause them to move toward the plane of the shoe bottom to position them in close relation to said plane for the tacking operation.

67. In a machine of the class described, the combination with grippers for pulling an upper over a last, of an upper fastening device movable lengthwise of the shoe into position for fastening the upper at the end of the toe, additional upper fastening devices mounted independently of said first-mentioned device and movable laterally of the shoe into position for fastening the upper at the sides of the toe, said fastening devices comprising tack holders and drivers, and means automatically operative to move said tack holders toward the plane of the shoe bottom for the upper fastening operation.

68. In a machine of the class described, the combination with means for pulling an upper over a last, of an upper fastening device movable lengthwise of the shoe into position for fastening the upper at the end of the toe, additional upper fastening devices movable laterally of the shoe into position for fastening the upper at the sides of the toe, said devices comprising tack holders and tack driving mechanism, and means controlled by said tack driving mechanism for moving said tack holders toward the plane of the shoe bottom in time relation to the tack driving operation.

69. In a machine of the class described, the combination with means for pulling an upper over a last, of upper fastening means movable inwardly into upper fastening position, operating mechanism for imparting inward movement yieldingly to said upper fastening means comprising a spring connection arranged to give way when said fastening means has arrived at its limit of inward movement to permit the actuation of the fastening means by continued movement of said mechanism, and supplemental means for holding said fastening means from outward return movement during the continued movement of said operating mechanism.

70. In a machine of the class described, the combination with means for pulling an upper over a last, of upper fastening means movable inwardly into upper fastening position, operating mechanism for imparting inward movement to said upper fastening means comprising a spring-controlled wedge member arranged to slip in response to resistance to the inward movement of said fastening means to permit the actuation of the fastening means by continued movement of said mechanism, and supplemental means to assist in moving said fastening means in-

wardly and for holding it from outward return movement during said continued movement of the operating mechanism.

71. In a machine of the class described, the combination with means for pulling an upper over a last, of tack driving means movable inwardly into upper fastening position, operating mechanism for imparting inward movement to said tack driving means comprising a spring-controlled wedge member arranged to slip when said driving means has arrived at its limit of inward movement to permit the driving means to be released by continued movement of said mechanism, and supplemental spring means arranged to be subjected to stress by the continued movement of said wedge member to assist in holding said tack driving means from outward return movement.

72. In a machine of the class described, the combination with means for pulling an upper over a last, of an arm mounted to swing inwardly toward the shoe and having tack driving means thereon, means for swinging said arm inwardly comprising a slide and a spring-controlled wedge block thereon arranged to effect a yielding connection with said arm and to slip in response to resistance encountered by the arm to permit the release of the driving means by continued movement of the slide, and a supplemental yielding member carried by said slide and arranged to assist in moving the arm inwardly and to hold the arm at its limit of inward movement.

73. In a machine of the class described, the combination with means for pulling an upper over a last, of an arm mounted to swing inwardly toward the shoe and having tack driving means thereon, means for swinging said arm inwardly comprising a slide and a spring-controlled wedge block thereon arranged to effect a yielding connection with said arm and to slip when said arm has arrived at its limit of inward movement to permit the release of the driving means by continued movement of the slide, and a spring plunger carried by said slide and arranged to bear with increasing pressure on the arm to hold it at its limit of inward movement during the continued movement of the slide.

74. In a machine of the class described, the combination with means for pulling an upper over a last, of an arm mounted to swing inwardly toward the shoe and having tack driving means thereon, an operating member arranged to swing said arm to its limit of inward movement and then by continued movement to actuate the driving means, and a spring plunger carried by said operating member and arranged to yield in a direction substantially parallel to the direction of movement of said arm to hold the arm with increasing pressure against return

outward movement at the time when said driving means is actuated.

75. In a machine of the class described, the combination with means for pulling an upper over a last, of side arms mounted to swing inwardly toward the shoe and having overlaying and fastening devices thereon, operating mechanism for imparting inward movement to said arms comprising spring plungers directed inwardly against the outer faces of the arms to move them inwardly, said plungers being yieldable in directions substantially parallel to the directions of movement of the respective arms after the arms have arrived at their limits of inward movement to permit the actuation of the fastening devices by continued movement of said mechanism.

76. In a machine of the class described, the combination with means for pulling an upper over a last, of side arms movable inwardly at opposite sides of the shoe and having overlaying and fastening devices thereon, operating means for swinging said arms inwardly comprising wedge blocks arranged to slip in response to resistance to the inward movement of said arms to permit the fastening devices to be rendered operative by continued movement of said operating means, and supplemental spring means arranged to assist in moving the arms inwardly and to be subjected to stress by said operating means for holding the arms against outward movement in the fastening operation.

77. In a machine of the class described, the combination with means for pulling an upper over a last, of front and side arms movable respectively lengthwise and laterally of the shoe and having overlaying and fastening devices thereon, operating means for moving said arms inwardly into upper fastening position comprising spring connections arranged to give way when said arms have arrived at their limits of inward movement to permit the fastening devices to be rendered operative by continued movement of the operating means, and supplemental devices automatically operative to hold said arms from outward return movement during the operation of the fastening devices.

78. In a machine of the class described, the combination with means for pulling an upper over a last, of front and side arms movable respectively lengthwise and laterally of the shoe and having overlaying and fastening devices thereon, operating means for moving said arms inwardly into upper fastening position comprising connections arranged to slip when said arms have arrived at their limits of inward movement to permit the fastening devices to be rendered operative by continued movement of the operating means, and spring plungers arranged to bear on said front and side arms with in-

creasing pressure in the continued movement of said operating means to hold the arms from outward movement during the operation of the fastening means.

79. In a machine of the class described, the combination with means for pulling an upper over a last, of a wiper support movable lengthwise of the shoe and having toe embracing wipers and upper fastening means thereon, yieldable operating mechanism connected to said wiper support for advancing said support to its limit of movement and operative by continued movement to actuate the upper fastening means, and supplemental means for holding said wiper support from outward return movement during the fastening operation.

80. In a machine of the class described, the combination with means for pulling an upper over a last, of a front arm movable lengthwise of the shoe, toe embracing wipers and upper fastening means carried by said arm, operating mechanism for moving said arm inwardly to advance the wipers over the shoe comprising a member arranged to yield in response to resistance to inward movement of the arm to permit the actuation of the fastening means by continued movement of said operating mechanism, and supplemental means controlled by said operating mechanism to assist in moving the arm inwardly and for holding the arm from outward return movement in the upper fastening operation.

81. In a machine of the class described, the combination with means for pulling an upper over a last, of overlaying and fastening mechanism mounted for inward movement over the shoe, operating means for imparting inward movement to said mechanism comprising a member arranged to yield in response to resistance to said inward movement to permit the actuation of the fastening mechanism by continued movement of the operating means, means for effecting relative movement of the shoe and the overlaying means in a direction transverse to the plane of the shoe bottom to increase the pressure on the shoe, and supplemental means for holding said overlaying and fastening mechanism from outward return movement when said increased pressure is applied.

82. In a machine of the class described, the combination with means for pulling an upper over a last, of a support movable inwardly toward the shoe and having a wiper and tack driving means thereon, operating mechanism connected to said support to move it inwardly comprising a wedge block arranged to slip when said support arrives at its limit of inward movement to permit the tack driving means to be rendered operative by continued movement of said mechanism, means for effecting relative movement of the shoe and said support in a direction

transverse to the plane of the shoe bottom to increase the pressure of the wiper on the shoe, and supplemental means controlled by said operating mechanism for holding the support at its limit of inward movement when said increased pressure is applied. 70

83. In a machine of the class described, the combination with means for pulling an upper over a last, of front and side arms movable inwardly toward the shoe and having overlaying and fastening means thereon, operating mechanism for moving said arms inwardly comprising members arranged to give way when the arms arrive at their limits of inward movement to permit the actuation of the fastening means by continued movement of said mechanism, means for moving said arms transversely of the plane of the shoe bottom to increase the overlaying pressure, and spring plungers carried by said operating mechanism and arranged to bear on the outer faces of the arms to hold the arms from outward return movement when said increased pressure is applied. 75 80

84. In a machine of the class described, the combination with means for pulling an upper over a last, of side arms movable laterally of the shoe and having upper fastening devices thereon, side clamps for the shoe mounted independently of said arms and having abutment faces thereon, and stop screws on said arms for engaging said faces to limit the inward movement of the arms, said screws being adjustable to vary the limit 90 95 of movement of the arms. 100

85. In a machine of the class described, the combination with means for pulling an upper over a last, of toe embracing wipers for wiping the margin of the upper about the toe into lasted position, side arms movable laterally of the shoe and having upper fastening devices thereon, said arms having also members thereon for engaging the wipers and forcing them inwardly over the shoe, means for variably limiting the inward movement of said arms, and devices rotatable to adjust said wiper engaging members for varying the limit of movement of the wipers relatively to the movement of the arms. 105 110 115

86. In a machine of the class described, the combination with means for pulling an upper over a last, of toe embracing wipers for wiping the margin of the upper about the toe into lasted position, side arms movable laterally of the shoe and having upper fastening mechanism thereon, members carried by said arms for engaging the wipers and forcing them over the shoe, means for limiting the movement of the arms comprising devices rotatable to vary their limits of movement to determine the position of the fastening mechanism relatively to the shoe, and devices for adjusting said wiper engaging members to vary the position of the 120 125 130

wipers relatively to the fastening mechanism.

87. In a machine of the class described, the combination with means for pulling an upper over a last, of upper fastening means comprising a plurality of tackers movable inwardly over the shoe, said tackers being relatively adjustable inwardly or outwardly in relation to the shoe, and rotatable members connected respectively to different tackers for adjusting them in or out by the turning movement of said members.

88. In a machine of the class described, the

combination with means for pulling an upper over a last, of a front arm movable lengthwise of the shoe and having wipers and tackers thereon, said tackers being relatively adjustable lengthwise of the shoe, and threaded members connected respectively to different tackers and having nuts thereon operative by turning movement to adjust said tackers lengthwise of the shoe.

In testimony whereof I have signed my name to this specification.

BERNHARDT JORGENSEN.
